UNITED STATES PATENT OFFICE.

FREDERICK H. UNTIEDT, OF WASHINGTON, DISTRICT OF COLUMBIA.

COMBINED CORKSCREW AND CORK BORER.

Application filed April 29, 1927. Serial No. 187,548.

This invention relates to a combined corkscrew and corkborer and it comprises a corkscrew having a helical screw portion or the like further provided with a sheath, advantageously cylindrical, such as a tube provided with a cutting edge, disposed about said screw portion and adapted to bore a hole in a cork and to retain and withdraw the bored out portion of the cork.

Many of the proprietary preparations such as astringents, hair tonics, dandruff removers and the like are bottled in bottles provided with cork stoppers. In dispensing the contents of bottles containing such preparations, there is a need for an exceedingly inexpensive, easily constructed corkscrew not only adapted to withdraw the cork, which is usually firmly inserted in the mouth of the bottle during bottling, but to also bore a hole in the cork whereby the contents of the bottle may be "shaken" out in much the same way as the contents of bay rum bottles is dispensed. Such bottles usually have a cork stopper of special construction provided with an arrangement whereby the inverted shaking of the bottle dispenses a small volume of the contents at a time.

I have found that the contents of a bottle may be "shaken" out through an ordinary cork in the mouth of the bottle if the cork is provided with a hole of small diameter, say three-sixteenths of an inch.

It is therefore an object of this invention to devise a corkscrew which is adapted to bore a hole in a cork for the purposes above mentioned. It is a further object of this invention to devise a combined corkscrew and corkborer easily assembled at but little cost so as to make it readily distributable gratis with bottled preparations of the character described and the like.

In the accompanying drawings I have illustrated one mode of applying my invention, it being understood however that I do not wish to be limited to the precise form of construction shown.

In the drawings:

Figure 1 shows in perspective a part of a bottle provided with a cork and illustrating the position of the combined corkscrew and corkborer when in use.

Figure 2 is a sectional view through the neck of a bottle showing a cork therein with the corkscrew and corkborer in place.

Figure 3 is a top section taken along the line 3—3 of Figure 2 and

Figure 4 illustrates an advantageous method of forming the corkscrew and corkborer.

In the drawings, like numerals refer to like parts.

Referring more particularly to Figure 2, 8 represents the neck of a bottle having a cork 5 in the mouth thereof. The corkscrew and corkborer is indicated by the elements 1, 2, 3 and 4. It comprises a corkscrew having a ring or handle 1 and a screw portion 2, shown in the form of a helix, adapted to screw into the cork. Disposed about the screw 2 is a cylindrical sheath or tubular cutter 3 fastened to the ring 1 by flared out portions 4 bent around and fastened to the ring 1. The sheath or tube, which acts as a cork borer, has its lower end 7 beveled or sharpened so that a cutting edge is formed. The lower end advantageously terminates slightly above the extremity of the screw 2 so that in use, the screw 2 enters the cork first. However, the lower end of the sheath or tubular cutter 3 may terminate above or below the end of the screw.

The sheath or tubular cutter should fit rather closely about the screw so that its diameter is not unduly great. The drawing, for the sake of clearness, shows the cork-boring sheath or tube as having a diameter almost twice as great as the screw. Actually, the internal diameter of the sheath need only be slightly greater than the diameter of the screw so that the sheath or tube is slightly spaced from the screw.

Figure 3, a cross section taken along 3—3 of Figure 2 shows the neck of the bottle, the cork, the screw 2 and the sheath or tube 3 as a top view.

An advantageous way of making the combined corkscrew and corkborer is illustrated in Figure 4. An ordinary wire corkscrew 1, 2, is provided in any known manner. A piece of tubing 3 is cut of the desired length. Its lower end is beveled to form a cutting edge 7 as shown. The upper end of the tube or sheath is slit for a way at 9 and the cut or slit end is then flared out. The sheath is slipped over the screw, the flared ends bent about and around the ring 1. Other fastening means may, of course, be employed.

In use, the assembled combined corkscrew and corkborer is screwed into the cork, the cork being advantageously retained in the mouth of the bottle during the operation.

The sheath or tubular cutter 3 is so proportioned to the cork that it is at least as long as the cork so that it can bore a hole all the way through the cork. As the screw penetrates the cork, the corkborer readily cuts a hole in the cork. After the cork is bored through, the corkscrew is withdrawn to gain access to the contents of the bottle. The contents may be readily shaken out through 10 the hole in the cork in small portions.

The bored out part 6 of the cork is securely retained within the sheath, the screw co-acting with the sheath or tube to hold the bored portion within the sheath. The screw 15 greatly facilitates boring the hole since it acts to draw the boring sheath into the cork. Furthermore, in my construction, small particles of cork do not break off to subsequently fall into the bottle and contaminate the 20 contents.

After a sufficient quantity of the contents of the bottle has been shaken out, the corkscrew and corkborer is reinserted in the hole in the cork, acting in this way as a stopper. 25 This is one of the advantages of providing a cutter adapted to retain the bored out portion of the cork. If it is desired to withdraw the cork as a whole, the corkscrew and corkborer is inserted in the hole and wobbled 30 a little to loosen the cork. If it is not desired to bore a hole through the cork, the corkscrew and corkborer is screwed into the cork but part way just as an ordinary corkscrew is manipulated.

35 The implement may be made of any suitable material. I have found brass an advantageous metal to use.

Having thus described my invention, what I claim is:

40 1. A combined corkscrew and corkborer having a helical screw adapted to screw into a cork and an annular sheath disposed about said screw, said sheath having a lower cutting edge and the upper end of said sheath being firmly fastened to the corkscrew by 45 means of flared out portions of the sheath.

2. A combined corkscrew and corkborer comprising a helical screw fastened to a holding ring, a sheath disposed about said 50 screw, said sheath being adapted to cut a hole in a cork, and means for firmly fastening said sheath to said ring, said means comprising flared out portions forming a continuation of the sheath, said flared out portions being wrapped about the ring and secured thereto.

60 3. A combined corkscrew and corkborer comprising a corkscrew and corkboring means carried by the corkscrew disposed in fixed relation thereto and adapted to retain and withdraw the bored out portion of the cork.

4. A combined corkscrew and corkborer comprising screw means adapted to screw

into a cork and a tubular cutter surrounding 65 said screw means in fixed relation thereto to cut a hole in a cork and to retain and withdraw the cut out portion of said cork.

5. A combined corkscrew and corkborer 70 comprising a corkscrew and a tubular cutter disposed adjacent the screw portion of said corkscrew and in fixed relation thereto said cutter being arranged to enter a cork to cut a hole therein subsequent to the entrance of the said screw portion and to retain and 75 withdraw the cut out portion of the cork.

6. A combined corkscrew and corkborer 80 comprising a corkscrew and a tubular cutter surrounding the screw portion of said corkscrew in fixed relation thereto but terminating above the lower end of said screw said cutter being adapted to retain and withdraw the cut out portion of the cork.

7. A combined corkscrew and corkborer 85 comprising a corkscrew having a helical cork-penetrating portion, and cork cutting means disposed about said helical portion in fixed relation thereto to cut a hole in a cork during the penetration of the helical portion and to retain substantially all of the cut out 90 portion of the cork.

8. A combined corkscrew and corkborer 95 comprising a corkscrew having a cork-penetrating portion and means carried by the corkscrew to cut a circular hole in a cork subsequent to the entrance of the cork-penetrating portion of the corkscrew and to retain and withdraw the cut out portion of the cork.

9. A combined corkscrew and corkborer 100 having a helical screw adapted to screw into a cork and a tubular cutter disposed about said screw in fixed relation thereto to cut a hole in said cork during the penetration of the screw and to retain and withdraw the cut out portion of the cork.

10. A combined corkscrew and corkborer 105 having a helical screw adapted to screw into a cork and an annular sheath disposed about said screw in fixed relation thereto and slightly spaced therefrom, said sheath having a lower cutting edge to cut a hole in a cork during the penetration of the screw.

11. A combined corkscrew and corkborer 110 having a helical screw adapted to screw into a cork, and an annular sheath disposed about said screw in fixed relation thereto and spaced therefrom, said sheath having a lower cutting edge terminating slightly above the lower end of the screw.

12. A combined corkscrew and corkborer 115 comprising a corkscrew and corkboring means carried by the corkscrew disposed in fixed relation thereto and adapted to retain and withdraw the portion of the cork penetrated by the screw.
